UNITED STATES PATENT OFFICE.

THOMAS P. SHEAN, OF CHICAGO, ILLINOIS.

WELL-BORING APPARATUS.

1,348,325.

Specification of Letters Patent.

Patented Aug. 3, 1920.

Application filed October 26, 1917. Serial No. 198,560.

To all whom it may concern:

Be it known that I, THOMAS P. SHEAN, a citizen of the United States, residing at Chicago, in the county of Cook and State 5 of Illinois, have invented certain new and useful Improvements in Well-Boring Apparatus, of which the following is a specification.

The present invention is related to well- 10 boring apparatus of that type primarily for use in the digging of wells, such as in oil and gas operations, where it is necessary to sink boring tools to great depth.

As distinguished from the usual type of 15 apparatus referred to the invention aims to provide a unitary structure complete in itself and provided with a suitable motor for effecting the operation of the cutting tool, the entire structure being designed to 20 penetrate the earth as the cutting operation progresses, and to follow the line of cut, thereby dispensing with the use of sectional drill rods commonly employed and the attendant annoyance and expense accompanying 25 their loss and attempted recovery.

A further object of the present invention 30 is the provision of novel and efficient means for maintaining the apparatus in proper relation to the cut as the penetration progresses, whereby to guide the apparatus in the cutting operation and insure the formation of a perfectly straight opening.

While the foregoing is a general statement of the primary objects of the invention 35 it will be apparent, as the nature of the improvements is better understood, that other objects are also sought to be accomplished, the invention consisting in the novel features of structure and combinations of parts 40 hereinafter fully described, illustrated in the accompanying drawings and finally pointed out in the appended claims. In this connection it is to be noted that the construction illustrated and described is not to be taken 45 in a limiting sense but as illustrative only of an embodiment of the invention.

In the accompanying drawings—

Figure 1 is a side elevation of a well-boring apparatus constructed in accordance 50 with the present invention;

Fig. 2 is an enlarged horizontal sectional view on the line 2—2 of Fig. 1;

Fig. 3 is an elevation on an enlarged scale

of the drill and reamers associated therewith; and

Fig. 4 is an inverted horizontal sectional view on the line 4—4 of Fig. 3.

Referring now in detail to the accompanying drawings, the numeral 10 designates a supporting rod having at one of its ends provision, such as an eye 11, for the attachment thereto of a suspensory cable 12 by means of which the apparatus is sustained in relation to the well being drilled and removed therefrom on completion of the work or as occasion may require. At the other end of the rod 10 is arranged a head 13, the latter being connected to said rod in any approved manner, to one end of which head 13 is attached a plurality of guide rods 14. These 70 guide rods extend upwardly from said head 13 and include lower straight portions 15, upper straight portions 16, and intermediate inclined portions 17 which serve to connect the portions 15 and 16. The straight 75 portions 15 and 16 lie parallel with the supporting rod 10, but by reason of the inclination of the intermediate portions 17 the upper portions 16 are spaced farther from the rod 10 than are the portions 15 so as to contact the walls of the well as the apparatus penetrates the same. The portions 16 are relatively long and in their contact with the well walls serve to maintain the rod 10 parallel therewith and thereby guide the apparatus in a straight line as penetration 80 proceeds. The upper ends of said rods 14 are curved inwardly, as at 18, to insure their freedom of movement over the well walls when the apparatus is being withdrawn from 85 the well or raised therein, and said straight portions 16 are held rigidly with respect to the supporting rods 10 by a plurality of attaching arms 19 one of which is bolted at its outer end, as at 20, to the inner face of 90 each of the straight portions 16. The inner ends of the arms 19 are curved, as at 21, and connected by bolts 22, or their equivalents, to a perforated anchoring plate 23 which surrounds the supporting rod 10. By proper 95 adjustment of the attaching arms 19 with respect to the plate 23, when the bolts 22 are loosened, the portions 16 of the guide arms 14 may be moved toward or away from the rod 10 to adapt the spacing of the portions 100 16 to varying diameters of wells. Further-

more, the portions 16 will automatically adjust themselves with respect to the rod 10 if the bolts 22 are permitted to remain somewhat loose and thereby enable the portions 16 to move inwardly and outwardly under different diameters of the cut. In such action of the portions 16 the bolts 22 will act as pivot points thus enabling the plate 23 to rotate partially about the rod 10 to accommodate the movement of the portions 16.

The tool of the herein described apparatus is of the rotary type, as presently will more fully appear, and for its operation a motor 24 is employed. This is preferably an electric motor, the current therefor being supplied by suitable conductors (not shown) leading from the surface of the ground at which point suitable controlling devices will also be located. The motor 24 is housed by a casing 25 carried by the end of the head 13 opposite to that to which the guide rods 14 are connected and properly protecting the motor against the sludge arising in connection with the drilling operation, and operatively related to the armature shaft of said motor, as by a proper coupling capable of effecting disconnection, is an elongated drill stock 26. At the lower end of the stock 26 is a bit 27 of any approved form for effecting initial penetration of the earth. By the bit the excavation is started. Its diameter, however, is essentially less than the diameter which it is desired to impart to the well, for the obvious purpose of not imposing on the bit the entire work of excavation. For enlarging the cut, therefore, it is proposed to utilize a plurality of reamers, designated by the numeral 28, each of which is designed to impart a different diameter of enlargement than the contiguous ones. These reamers are in the form of cutter bars the ends of which are beveled as at 29, to insure their cutting action, and said reamers are received by and fit within transverse slots 30 formed in the stock 26 in which they are held by fastening wedges 31. This provides for the ready removal of the reamers when it is desired to substitute different lengths for varying diameters of wells. It will also be noted that the alternate reamers are arranged at right angles to the adjacent ones, thus affording an equal distribution on the stock 26 of strain imposed on the reamers by their contact with the earth. Furthermore, they progressively increase in length from the lowermost one adjacent to the bit 27 to the topmost reamer, the length of the latter being the diameter which it is desired ultimately to impart to the well.

When boring deep wells various strata differing in degrees of hardness are encountered. In a unitary structure such as herein disclosed there must, therefore, be provision for varying the weight for advancing the apparatus, otherwise strata harder than the

relative softer ones might impede the penetration of the drill. To provide for this a plurality of weights 32 is employed, said weights encircling the supporting rod 10 and being suspended by a cable 33 which extends to the surface of the ground. By this cable suspension the weights exert no pressure on the apparatus normally. When, however, occasion arises for their use the cable 33 is slackened, whereupon the weights successively gravitate, the lowermost weight coming to rest upon the upper end of the head 13, and the uppermost weight becoming seated on the lowermost one. In this manner the requisite additional weight may be supplied to the head 13 to force the bit 27 downwardly and overcome the resistance offered by the harder strata as they are met.

From the foregoing description the operation and advantages of the herein described invention will be readily understood. When it is desired to bore a well the stock 26 is connected to the armature shaft of the motor 24, and the apparatus positioned at the point at which it is desired to sink the well. The motor being set in operation, it will be obvious that the initial penetration of the ground is effected by the bit 27. As penetration progresses the reamers 28 successively cut the boring to their several diameters until the uppermost reamer 28 is reached, at which point the greatest diameter of the well is obtained. As the apparatus gradually descends into the cut the straight portions 16 of the guides 14 come into contact with the walls of the well and follow the latter, thereby insuring a straight cut to the well as the apparatus gradually progresses in its penetration. If, in the progress of the boring operation, strata be encountered offering relatively harder resistance than other strata, the cable 33 is slackened, thereby permitting the weight 32 to descend on to the upper end of the head 13, thus imposing the added weight of these elements, and enabling the drill to meet the resistance offered by the harder strata. Normally, however, the weights 32 are suspended by the cable 33 to free the structure of the effect thereof.

I claim:

1. In an apparatus of the class described, the combination with a support, of a head connected to said support, a motor connected to one end of said head, a cutting tool associated with said motor, and a plurality of rods connected to the other end of said head for guiding the apparatus as the same penetrates the cut, said guiding rods extending upwardly from said head and surrounding said support in spaced relation to the latter.

2. In an apparatus of the class described, the combination with a support, of a head connected to said support at one of its ends, a motor supported by said head, a cutting

tool associated with said motor, and a plurality of guide rods connected to said head and extending in substantial parallelism with said support, said guide rods surrounding said support in spaced relation to the latter and serving to guide the apparatus as the latter penetrates the cut, and connections between said guide rods and said support for holding the free ends of said rods in proper relation to said support.

3. In an apparatus of the class described, the combination with a support, a motor carried thereby, a cutting tool associated with said motor, and means for imposing increments of weight on the motor.

4. In an apparatus of the class described, the combination with a support, a motor carried thereby, a cutting tool associated with said motor, and means for imposing progressive increments of weight on the motor.

5. In an apparatus of the class described, the combination with a support, a motor carried thereby, a cutting tool associated with said motor, a plurality of weights adapted for coöperation with the motor for effecting penetration of the cutting tool when the latter meets with increased resistance from the material being penetrated, and means for depositing said weights progressively on the motor and its cutting tool to progressively increase the weight thereof.

6. In an apparatus of the class described, the combination with a support, a motor carried thereby, a cutting tool associated with said motor, a plurality of weights adapted for coöperation with the motor for effecting penetration of the cutting tool when the latter meets with increased resistance from the material being penetrated, and connections between said weights whereby the same may be deposited successively on the motor and its cutting tool to progressively increase the weight thereof.

7. In an apparatus of the class described, the combination with a support, a motor carried thereby, a cutting tool associated with said motor, a plurality of weights adapted for coöperation with the motor for effecting penetration of the cutting tool when the latter meets with increased resistance from the material being penetrated, and a flexible supporting means for said weights whereby the same may be deposited successively on the motor and its cutting tool to progressively increase the weight thereof.

8. In an apparatus of the class described, the combination with a support, a motor carried thereby, a cutting tool associated with said motor, a plurality of weights adapted for coöperation with the motor for effecting penetration of the cutting tool when the latter meets with increased resistance from the material being penetrated, and a supporting cable connected to said weights and normally holding the same at separated points and

free from contact with the motor, said weights being deposited successively on the motor and its cutting tool to progressively increase the weight thereof upon the slackening of said cable.

9. In an apparatus of the class described, the combination with a support, a motor arranged at one end thereof, a cutting tool associated with said motor, a plurality of weights surrounding said support and slideable along the same for coöperation with the motor for effecting penetration of the cutting tool when the latter meets with increased resistance from the material being penetrated, and means for normally sustaining said weights separated with respect to each other and free from contact with the motor.

10. In an apparatus of the class described, the combination with a support, a motor arranged at one end thereof, a cutting tool associated with said motor, a plurality of weights surrounding said support and slideable along the same for coöperation with the motor for effecting penetration of the cutting tool when the latter meets with increased resistance from the material being penetrated, and a flexible cable connected to said weights and normally sustaining the same in separated relation with respect to each other to free the weights from contact with the motor, said weights being deposited successively on the motor to progressively increase the weight thereof when said cable is slackened.

11. In an apparatus of the class described, the combination with a support, of a head connected to one end of said support, a motor connected to one end of said head and supported thereby, a cutting tool associated with said motor, and a plurality of guide rods connected to the other end of said head and surrounding said support in substantial parallelism therewith but spaced therefrom, said guides extending upwardly from said head and including parallel portions adapted to contact with the walls of the cut and guide the apparatus as the latter penetrates the cut.

12. In an apparatus of the class described, the combination with a support, of a head connected to one end of said support, a motor supported by said head, a cutting tool associated with said motor, and a plurality of guides arranged in radial relation to said support and including parallel portions connected to said head, intermediate inclined portions, and parallel portions offset with respect to said support at greater spacing therefrom than the first mentioned parallel portions, said offset parallel portions being adapted to contact the walls of the cut and guide the apparatus as the latter penetrates the cut.

13. In an apparatus of the class described,

the combination with a support, a motor carried thereby, a cutting tool associated with said motor, means for guiding the apparatus as the same penetrates the cut, and means for 5 imposing increments of weight on the motor.

14. In an apparatus of the class described, the combination with a support, a motor carried thereby, a cutting tool associated with said motor, means for guiding the apparatus 10 as the same penetrates the cut, and means for imposing progressive increments of weight on the motor.

15. In an apparatus of the class described, the combination with a support, a motor carried 15 thereby, a cutting tool associated with said motor, a plurality of guides arranged in radial relation to said support and including parallel portions at their respective ends and intermediate connecting portions, the parallel portions at one end of said guides being spaced from said support at greater distance than the opposite parallel portions and serving to contact the walls of the cut to guide the apparatus as the latter penetrates the 20 cut, and means for anchoring said greater-spaced portions to said support for holding said portions in rigid relation to the support.

16. In an apparatus of the class described, the combination with a support, of a head arranged 25 at one end thereof, a motor carried by

said support adjacent to said head, a cutting tool associated with said motor, a plurality of guides mounted at one of their ends on said head, said guides extending in substantial parallelism to said support, an anchoring plate arranged about said support adjacent to the other ends of said guides, and connections between said guides and said anchoring plate. 35

17. In an apparatus of the class described, 40 the combination with a support, of a head carried by said support and arranged adjacent one of its ends, a motor carried by said head, a plurality of guide rods mounted at one of their ends on said head and extending in substantial parallelism with said support, an anchoring plate arranged about said support adjacent to the other end of said guide rods, and a plurality of attaching arms arranged between said guide rods and said anchoring plate for connecting the guide rods with said anchoring plate. 45

In testimony whereof I have hereunto signed my name in the presence of two subscribing witnesses.
